UNITED STATES PATENT OFFICE.

ALEXANDER D. ELLIOTT, OF VIOLA, ILLINOIS.

NECKTIE HOLDER.

Application filed June 3, 1922. Serial No. 565,617.

To all whom it may concern:

Be it known that I, ALEXANDER D. ELLIOTT, a citizen of the United States, residing at Viola, in the county of Mercer and

5 State of Illinois, have invented certain new and useful Improvements in Necktie Holders, of which the following is a specification.

This invention relates to improvements in neck tie holders particularly adapted, 10 though not necessarily limited in its use

with a neck tie of what is commonly known as the four-in-hand type, and has for one of its objects to provide an improved holder of this character on which the tie may be tied or knotted and the holder with the tie thereon quickly and securely fastened within the fold of a collar by engagement with the collar button, and as quickly removed or detached.

20 Heretofore with neck tie holders of this general character, considerable difficulty and inconvenience has been experienced in that the knot or folded portion of the tie is not held close to the top of the folded portion 25 of a turned down collar and it has been necessary to rely solely upon the fastening of the holder to the collar button. Other devices of this character embody clips which grip the edges of the outer fold of the collar with the result that the tie will soon 30 work out of its proper position and often drops off.

To overcome these difficulties and objections and to provide an improved tie holder 35 embodying means adapted to exert a pressure upon the collar button and the top edge of the tie so that the top edge of the tie will be forced into the top folded portion of a turned down collar, and retain the tie in 40 such a position, is another one of the objects of the present invention.

A still further object is to provide an improved neck tie holder of this character which will be of a simple, durable, light and 45 cheap construction, and which will be effective and efficient in operation.

To the attainment of these ends and the accomplishment of other new and useful objects as will appear, the invention consists 50 in the features of novelty in substantially the construction, combination and arrangement of the several parts hereinafter more fully described and claimed and shown in the accompanying drawing illustrating this 55 invention and in which—

Figure 1 is a front elevation of a turned

down collar showing a neck tie held in position by means of a holder constructed in accordance with the principles of this invention.

60

Figure 2 is a rear view of the holder with the tie attached thereto and showing a portion of the collar in section, the full lines of the holder showing the normal position thereof and the dotted lines the compressed position.

65

Figure 3 is a detailed elevation of the holder.

The holder consists essentially of a body portion preferably constructed of a single 70 piece of resilient wire and bent into shape to form an enlarged and elongated loop having a top portion which is depressed as at 10 to form laterally spaced upwardly projecting shoulders 11. The free ends of the 75 wire are bent towards each other and twisted as at 12 to form resilient walls 13, the twisted portion 12 being disposed intermediate the ends of the loop. The extremities 14 of the twisted portion 12 are shaped 80 to form a downwardly opening seat 15.

The loop thus formed is normally of a height somewhat greater than the distance between the collar button 16 and the top edge 17 of the folded down portion of a 85 collar 18.

The tie is looped or knotted about the depressed portion 10 of the upper wall of the loop so that the upper edge of the knot of the tie will stand between walls 11, and 90 encompass the portion 10 of the loop, so that the tie will be held against lateral shifting movement upon the holder. The walls 11 project beyond the part of the tie that is in the depressed portion of the holder 95 so as to extend well into the folded portion of the collar in advance of the tie. This arrangement prevents the tie from causing the folded edge of the collar to become distorted.

100

In use the holder is positioned so that the body portion thereof embodying the resilient walls 13 will stand behind the knot 20 of the tie and after the collar 18 has been put on in the usual manner, the 105 holder together with the tie secured thereto is passed under the folded down portion of the collar and is moved upwardly until the upper edges of the shoulders 11 engage the edge 17 of the folded down portion of 110 the collar. In this position the seat 15 of the holder on the twisted extremity 12 will

be normally disposed beneath the collar button 16. The resilient walls 13 of the holder are then compressed to a sufficient extent that the seat 15 may be engaged over the
5 shank of the collar button 16 thereby placing the holder under compression and forcing the same between the collar button 16 and the upper edge 17 of the collar. This will shove or move the upper edge of the
10 neck tie in close proximity to the edge 17 of the folded down portion of the collar.

When it is desired to remove the tie all that is necessary is to furnish compress the resilient walls 13 of the holder until the seat
15 can be disengaged from the shank of the collar button 16, after which the tie may be readily removed.

The extremities 14 are preferably twisted as shown so as to protect the tie against the
20 edges of the wire and also to serve as a means for assisting in detaching the seat from the shank of the collar button.

While the preferred form of the invention has been herein shown and described
25 it is to be understood that various changes may be made in the details of construction

and in the combination and arrangement of the several parts, within the scope of the claim, without departing from the spirit of this invention.

30

What is claimed as new is:—

A neck tie holder consisting of a single piece of resilient wire like material bent to form a loop, the ends of the material being twisted together with the extremities 35 of the ends forming a medial downwardly opening seat adjacent the lower wall of the loop, said seat being adapted to engage over a portion of the upper wall of the loop being depressed to form spaced upwardly projecting shoulders at the ends of the loop, said shoulders being of a height to project above the portion of the tie which engages in said depressed portion, whereby the 40 45 shoulders will project beyond the tie and into the folded portion of the collar.

In testimony whereof I have signed my name to this specification, on this 1st day of June, A. D. 1922.

ALEXANDER D. ELLIOTT.
